PATTERNING CONTROL MEANS FOR
KNITTING MACHINES

John Lawson, Bristol Highlands, and Robert H. Lawson, Pawtucket, R. I., assignors to Hemp-hill Company, Central Falls, R. I., a corporation of Massachusetts

Original application July 9, 1927, Serial No. 204,590, now Patent No. 1,858,301, dated May 17, 1932. Divided and this application April 6, 1932, Serial No. 603,660

18 Claims. (Cl. 66—1)

This application is a division of our application Ser. No. 204,590, filed July 9, 1927, now Patent No. 1,858,301, May 17, 1932.

This invention relates to a device or means for effecting the arrangement of strips or members provided with removable butts, the butts which are to make the pattern being retained and the others being removed. The removable strips or members, after being arranged in accordance with the desired pattern, are at the desired time transferred in their pattern arrangement to a drum or receiving member of a knitting machine, such, for example, as the jacquard drum or carrier disclosed in our Patent No. 1,872,598, August 16, 1932.

Referring more particularly to the drawing:

Fig. 1 is a plan view of a card or paper with pattern thereon for use in preparing the pattern or lay-out for a jacquard machine, particularly for reverse plating;

Fig. 2 is a plan view of a plate or member upon which the jack-like devices of the jacquard drum are arranged to produce a pattern based upon such a pattern as indicated in Fig. 1; and

Fig. 3 is a vertical section of the plate or member shown in Fig. 2.

In Figs. 1, 2, and 3, we have disclosed means whereby jack-like members for a jacquard drum or carrier may be arranged in accordance with a pattern. In our said Patent No. 1,872,598, we have disclosed an entire jacquard mechanism whereby normal and reverse plating may be effected according to any pattern. In accordance with the mechanism there disclosed, the pattern drum is provided with a large number of jacquard like strips preferably equal in number to one half the number of needles. The said strips are adapted to be inserted in lengthwise extending grooves upon the periphery of a drum or barrel and they are provided with lugs according to the pattern. As disclosed in said Patent No. 1,872,598, each of said strips may have forty-eight projections.

It is the purpose of the present application of our invention to provide a device or series of devices in each of which the jack-like strips may be arranged according to a pattern in a readily removable manner, so that when it is desired to change the pattern in the jacquard machine, the jack-like strips therein are removed and those in the device shown in Fig. 2 are substituted therefor in the order in which they are supported in the said device. In preparing for the insertion of the jack-like strips in the device of Fig. 2, we previously prepare a card or paper 1, as shown in

Fig. 1. This card or paper is ruled or marked to present the desired pattern precisely as it appears in the stocking or other fabric, the colors being indicated by different hatching or markings generally indicated at 2.

We provide a tray or plate 3 having at its upper and lower edges filling or spacing strips 4, 5, and fixedly secured to the strip 4 is a holding strip 6. Upon the face of the plate or tray 3 is pasted or otherwise secured a paper 7. The paper 7 is provided with a plurality of longitudinally disposed lines or bands numbered 1-48 the said bands affording a convenient means, in connection with the markings on the pattern sheet 1, whereby the butts 12 which are to be removed can be readily determined. Furthermore, the fabric wales are indicated by numerals on the pattern sheet 1, numerals 1-9 being shown although it will be understood that all the vertically disposed lines, indicating wales, on the pattern sheet 1 are numbered; likewise the selector jacks or strips 11 are correspondingly numbered. Thus by providing the horizontal bands on the sheet 7 and by numbering the said bands and correspondingly numbering the sheet 1, and by numbering the wales indicated on the sheet 1 and the selector strips on the plate 3, it can be readily determined just what butts are to be removed from the selector strips 11 to produce a desired fabric pattern. Along the upper and lower edges of the tray 3 are secured strips 8, 9, and the said strips have aligning grooves therein equalling in number the number of the jack-like strips that are to be used in making the fabric. In the example given, the number of such strips is one half the needles of the machine. If desired, the color scheme of the pattern is indicated upon the paper 7 by different markings as indicated at 10. In Figs. 2 and 3, we have represented certain of the jack-like strips at 11, certain of the lugs or projections thereof being indicated at 12. Each said strip is provided with a reduced upper end 13 and in assembling the said jack-like strips upon the tray or plate 3, the said reduced ends 13 are inserted under the confining strip 6 in a proper groove of the upper strip 8.

In order to hold the jack-like strips in position on the tray or plate 3 until the particular design thereof is required, we provide a lower slide or member 14 having elongated slots 15 through 50 which pass screws 16 whereby the said slide or member is secured to the plate or tray 3.

By loosening the screws 16 the slide or member 14 is movable downward viewing Figs. 2 and 3, so as to permit the insertion of all the jack-like

strips, whereupon the said slide or member 14 is moved upwardly so as to engage and confine the lower reduced ends 17 of the jack-like strips. Then the screws 16 are tightened so as to secure 5 the slide or member 14 in position. The plate or tray 3 is now ready for use and a series of such trays may be provided for use as required.

In order to make use of the jack-like strips of any plate or tray, the jack-like strips that are in 10 the slots of the jacquard drum of the machine are removed and the strips 11 are substituted therefor in the precise order in which they appear upon the said plate or tray.

From the foregoing description, it will be 15 understood that by use of the support or plate 3 in connection with the pattern sheet 1 in the manner hereinbefore described, it is possible thereafter to transfer the jack-like elements or strips 8 to the pattern controlling elements of a 20 knitting machine, such as a jacquard drum, and without disturbing the relative arrangement of the said jack-like elements.

Having thus described one illustrative embodiment of the invention, it is to be understood 25 that although specific terms are employed, they are used in a generic and descriptive sense and not for purposes of limitation, the scope of the invention being set forth in the following claims.

We claim:

30 1. For use in connection with an independent knitting machine having removable jack-like strips controlling the movement of special sinkers in effecting changes in reverse plating, a support or member upon which a complete series of jack-like strips may be arranged according to a desired pattern and from which said jack-like strips may be quickly transferred to the support in the machine for said jack-like strips, said support having means for retaining the jack-like strips as arranged, said support also having indications thereon to facilitate the arrangement of the jack-like strips on the support in accordance with a desired pattern.

2. Pattern control means for knitting machines 45 but separate therefrom consisting of a support or member to receive a series of jack-like strips according to a pattern, said support having means for retaining the jack-like strips as arranged, said support also having indications thereon to facilitate the arrangement of the jack-like strips on the support in accordance with a desired pattern.

3. Pattern control means for knitting machines 55 but separate therefrom consisting of a support or member to receive a series of jack-like strips according to a pattern, and means to confine said strips temporarily to said support or member, said support also having indications thereon to facilitate the arrangement of the jack-like strips on the support in accordance with a desired pattern.

4. Pattern control means for knitting machines 65 but separate therefrom consisting of a support or member to receive a series of jack-like strips according to a pattern, said support or member being grooved for the reception of said strips, said support also having indications thereon to facilitate the arrangement of the jack-like strips on the support in accordance with a desired pattern.

5. Pattern control means for knitting machines 70 but separate therefrom consisting of a support or member to receive a series of jack-like strips according to a pattern, said support or member being grooved for the reception of said strips, and

means temporarily to secure said strips on said grooves, said support also having indications thereon to facilitate the arrangement of the jack-like strips on the support in accordance with a desired pattern.

6. For use in connection with an independent knitting machine having removable jack-like strips controlling the movement of instrumentalities to effect pattern changes, a support or member upon which a complete series of jack-like 10 strips may be arranged according to a desired pattern and from which said jack-like strips may be quickly transferred to the support in the machine for said jack-like strips, in combination with a sheet having thereon the pattern in 15 accordance with which the strips are to be arranged on said support or member, the support and sheet having corresponding indications to facilitate the arrangement of the said jack-like strips in accordance with the pattern on the sheet. 20

7. Pattern control means for knitting machines consisting of a support or member to receive a series of jack-like strips according to a pattern, in combination with a sheet having thereon the pattern in accordance with which the strips are to be arranged on said support or member, the support and sheet having corresponding designations to facilitate the arrangement of the jack-like strips in accordance with the pattern on the sheet. 30

8. Pattern control means for knitting machines consisting of a support or member to receive a series of jack-like strips according to a pattern, and means to confine said strips temporarily to said support or member, in combination with a 35 sheet having thereon the pattern in accordance with which the strips are to be arranged on said support or member, the support and sheet having corresponding designations to facilitate the arrangement of the jack-like strips in accordance with the pattern on the sheet.

9. Pattern control means independent of but adapted to be used in connection with knitting machines consisting of or including a support, said support having grooves within which jacks 45 are adapted to be received and retained in a desired prearranged order, said support also having indications thereon to facilitate the arrangement of the jack-like strips on the support in accordance with a desired pattern.

10. Pattern control means independent of but adapted to be used in connection with knitting machines consisting of or including a support, said support having a longitudinally extending recess within which the ends of jacks are adapted 55 to be received and retained in a prearranged order, said support also having indications thereon to facilitate the arrangement of the jack-like strips on the support in accordance with a desired pattern.

11. A support adapted to receive and retain jacks in a prearranged order, said support having two sets of aligned grooves, the said sets of aligned grooves being spaced from one another and adapted to receive opposite ends of the said jacks 65 and retain them as arranged, and pattern indications on the said support between said sets of aligned grooves, said pattern indications assisting in the proper arrangement of jacks in the said support.

12. A method of setting up pattern controlled elements corresponding to a given design consisting in assembling jack-like elements in a support and in accordance with the design in such a manner that the said elements can be subsequently 75

assembled in a pattern member of a knitting machine.

13. A method of setting up pattern controlled elements corresponding to a given design consisting in or including the arranging of jack-like elements, which initially have the same number of butts, in a support, removing some of the butts in accordance with the design shown on a chart, thereafter transferring the jack-like elements to the pattern controlling element of a knitting machine and without disturbing the relative arrangement of the said jack-like elements.

14. A method of setting up pattern controlled elements corresponding to a given design consisting in or including the arranging of jack-like elements, which initially have the same number of butts, in a support, removing some of the butts in accordance with the design shown on a chart by referring to the chart and support each of which has line designations corresponding in number to the maximum number of butts on the jack-like elements, thereafter transferring the jack-like elements to the pattern controlling element of a knitting machine and without disturbing the relative arrangement of the said jack-like elements.

15. A pattern arranging plate for assisting in setting up a machine for making a fabric pattern, said plate having transversely extending bands, and in combination therewith having like pattern elements transversely mounted in the plate and each having a series of removable pattern determining projections some of which are to be removed prior to assembly of the said pattern elements in the machine for making patterned fabric, the aforesaid bands providing a convenient means for determining which ones of

the projections shall be removed to effect the making of the desired pattern in a fabric.

16. A pattern plate for assisting in arranging the pattern elements of a machine for making fabric patterns, said plate having removably mounted therein a series of like pattern elements which are to be incorporated in the machine for producing the patterned fabric, the plate having numerals corresponding in number to the number of projections originally on each pattern element so that desired ones of the projections on the several pattern elements can be readily removed and the pattern elements assembled in the machine in appropriate order.

17. A pattern plate for assisting in arranging pattern elements in a machine adapted to make patterned fabric, said plate having two parallelly and longitudinally disposed recesses, one of such recesses being defined by an adjustable member which in a retracted position permits the ready insertion of pattern elements having projections to engage in the other mentioned recess, the construction being such that when an appropriate number of pattern elements are inserted, the member may be moved to retain the pattern elements in position, and means for retaining the said member in its last named position.

18. A pattern plate for assembly therewith of pattern elements, means on the plate for retaining the ends of the pattern elements, and means adjacent to such retaining means for maintaining the pattern elements in proper alignment, said means last mentioned consisting of notched strips within the notches of which the pattern elements are adapted to seat.
